UNITED STATES PATENT OFFICE.

WALTER R. SCHINDLER, OF LOS ANGELES, CALIFORNIA.

PAPER-CUPPING MACHINE.

Application filed June 15, 1921. Serial No. 477,752.

To all whom it may concern:

Be it known that I, WALTER R. SCHINDLER, a citizen of the United States, residing at Los Angeles, in the county of Los Angeles, 5 State of California, have invented new and useful Improvements in Paper-Cupping Machines, of which the following is a specification.

This invention has to do with a paper cupping machine, and it is an object of the invention to provide a simple, effective machine of that character.

A particular object of the invention is to provide a machine to effectively form paper cups and particularly comparatively large paper cups, such, for instance, as are used as hoods to protect young plants. It has been found in practice difficult to efficiently form comparatively large paper cups without tearing and thus spoiling many of them. 20 The present machine is entirely automatic and because of the novel means provided by the present invention will operate to very rapidly and accurately form sheets of paper 25 into cups without tearing them.

The construction of the die, provided by the present invention for forming the sheets of paper into cups, is a distinctive and important feature of the invention. The die 30 is simple in construction and operation yet is particularly effective in properly and permanently cupping the paper without tearing it.

The various objects and features of the invention, including those hereinabove mentioned, will be best and more fully understood from the following detailed description of a typical embodiment of the invention throughout which reference is had 40 to the accompanying drawings in which—

Fig. 1 is a plan view of the machine; Fig. 2 is an enlarged vertical longitudinal detail sectional view of the machine shown in Fig. 1, being a view taken as indicated by line 2—2 on Fig. 1; Fig. 3 is a transverse sectional view of the machine, being a view taken as indicated by line 3—3 on Fig. 2; Fig. 4 is an enlarged side elevation of a portion of the machine, being a view taken as indicated by line 4—4 on Fig. 1; Fig. 5 is an enlarged transverse sectional view of the machine, taken as indicated by line 5—5 on Fig. 1, showing the position in which the

male die is in as it is moved into engagement with the female die; Fig. 6 is a view 55 similar to Fig. 5, showing the position to which the male die is moved while it is in pressure engagement with the female die in order to iron the paper; Fig. 7 is an enlarged detail sectional view taken as indicated by line 7—7 on Fig. 1; Fig. 8 is an enlarged side elevation of a portion of the machine showing the position of the crank at the time the male die is moved into complete 60 engagement with the female die, the female die being shown in section to make clear the relative positioning of the male and female dies; Fig. 9 is a view similar to Fig. 8 showing the positioning of the crank at the time that the male die is held in pressure engagement with the female die; and Fig. 10 is an enlarged detail longitudinal sectional view 65 of the male and female dies showing them together.

The particular machine herein set forth to 75 illustrate the present invention comprises, generally, a frame 10, two female die parts 11, two male die parts 12, one adapted to co-operate with each of the female dies 11; a mechanism 13 for operating the male dies 80 12, and an automatic feeding mechanism 14 adapted to automatically feed sheets of paper to the co-operating male and female die parts. The die parts 11 and 12, the operating mechanism 13, and the feed mechanism 14, are all suitably arranged and mounted 85 on the frame 10. The female die parts 11, hereinafter termed the female dies, are spaced apart in the frame 10 and are oppositely disposed. The male die parts 12, hereinafter termed the male dies, are oppositely disposed, being mounted on opposite sides of a cross-head 15 arranged between the female dies 11 and carried by suitable 90 guides 16 supported by the frame 10. The crosshead 15 is reciprocated by the operating mechanism 13 so that each of the male dies 12 properly co-operate with a female die 11. There are two feeding mechanisms 14, one for feeding sheets of paper to each 95 pair of co-operating dies. With the general arrangement just described, a single operating mechanism 13 properly operates two separate and independent die mechanisms. In other words, by providing two die mechanisms in connection with the operation 100 105

mechanism, a cup is formed at each movement of the cross-head 15. By this particular arrangement the invention provides a simple, compact machine, capable of forming cups very rapidly.

The die mechanisms, each of which comprises a male die and a female die, and the feeding mechanisms 14, are identical in construction and operation, so, therefore, I will 10 proceed to describe in detail only one of the die mechanisms and the feeding mechanism for that particular die mechanism, it being understood, of course, that such description is applicable also to the other die mechanism 15 and its co-operating feed mechanism.

The female die 11 comprises, generally, three parts, an outer part 18, an inner part 19, and a central member or finger 20. The outer part is formed with a suitable flange 22 by which it is solidly mounted on a solid frame member 21. The inner part 19 of the female die is separate from the outer part 18 and is carried concentrically in the outer part 18 by a stem 23 carried in a suitable 25 guide 24. The stem 23 is preferably in the form of a tube and the guide 24 is preferably in the form of a tube which slidably carries the stem 23. The inner part 19 may be detachably carried at the outer end of 30 the stem 23, say, for instance, it may be screw-threadedly connected to the stem 23, in the manner clearly illustrated in Figs. 2 and 10 of the drawings. The outer part 18 of the female die is formed with a central 35 concentric opening 25 which is adapted to receive the inner part 19 so that the inner part can be moved into the outer part to a position where its face 26 forms a continuation of the face 27 of the outer part. A shoulder 28 is provided in the opening 25 to support the inner part 19 and prevent it being moved inwardly from the position where its face 26 forms a continuation of the face 27 of the outer part. A helical 40 spring 30 is arranged in the stem 27 and guide 24 between the inner part 19 and a plug 31 adjustably removably carried in the end of the guide 24. In practice the plug may be screw threaded in the end of the 45 guide 24 in the manner illustrated in the drawings. The spring 30 is under compression between the plug 31 and inner part 19, so that it tends at all times to hold the inner part 19 out into the outer part 18 in 50 a position such as is shown at the left in Fig. 2. It will be obvious how the pressure with which the part 19 is held out may be suitably regulated by adjusting the position of the plug 31 in the guide 24. The outward movement of the inner part may be 55 limited by a pin 170 extending from the guide 24 into a groove 171 in the stem 23.

The finger 20 is slidably carried in a suitable opening 33 formed concentrically in the 60 inner part 19 and has a head 34 formed at face 65

its outer end. The finger is adapted to be pushed or moved inwardly through the opening 33 until the head 34 seats in a suitable recess 35 formed in the inner part 19. When the head 34 is seated in the recess 35 70 it forms a continuation of the face 26 of the inner part 19. At the inner end of the finger 20 there is a head 36 slidably carried in a guide 37 extending rearwardly from the inner part 19 within the helical spring 30, stem 23 and guide 24, in the manner clearly illustrated in Fig. 10 of the drawings. A suitable plug 37^a is adjustably removably carried in the end of the guide 37 and a helical spring 38 is arranged in compression between the head 36 and plug 37^a to normally hold the finger 20 outwardly in the opening 33 in which position the head 34 is removed from the recess 35 and is substantially in line with the forward end or mouth of the outer portion 18, as clearly illustrated at the left in Fig. 2. The head 36 at the inner end of the finger 20 engages the inner part 19 to limit the outward movement of the finger 20. The pressure with which the finger 20 90 is held, may be suitably regulated by adjusting the position of the plug 37 in the guide 38. The construction herein so far described provides a female die formed of two relatively movable parts, an inner part and 95 an outer part, the inner part being normally held out in the outer part and being adapted to be moved inwardly in the outer part to a position where it forms a continuation of the outer part. Further, it will be readily 100 understood how the finger 20 is slidably carried in the inner part 19 and how it is normally held in position when the head 34 at its outer end is at the outer part of the die, and how it may be moved to a position where 105 its head 34 is seated in the recess 35 to fill the recess and form a continuation of the inner part 19. The construction provided by the present invention permits of the several parts of the female die being readily 110 separated or taken apart for purpose of inspection, repair, etc.

The male die 12 comprises, generally, an outer part 40 adapted to co-operate with the outer part 18 of the female die, an inner part 41 adapted to co-operate with the inner part 19 of the female die, and a finger 42 adapted to co-operate with the finger 20 of the female die. The outer part 40 of the male die is rotatably carried on the cross head 15 concentrically with the outer part 18 of the female die. The outer part 40 may be secured to the cross head 15 in any suitable manner. In the drawings it is shown formed with a flange part 44, which is engaged by a retaining ring 45 secured to the cross head 15 by suitable screws 46. The outer part 40 is formed with a surface 47 which conforms or corresponds to the surface 27 of the outer part 18 of the female 125 130

die, and has a surface 48 which forms an acute angle with the surface 47 and which corresponds to the surface 49 of the outer part 18 of the female die which forms an acute angle with the surface 27 thereof.

The inner part 41 of the male die 12 is detachably mounted on the outer end of a stem 50 which is slidably carried in a suitable guide 51 formed concentrically on the outer part 40. The inner part 41 has a surface 52 which corresponds or conforms with the surface 26 of the inner part 18 of the female die and which is adapted to form a continuation of the surface 47 of the outer part 40 when the inner part 41 is seated against the outer part 40 in the manner clearly shown in Fig. 10. A stop 53 is adjustably carried on the stem 50 and a suitable helical spring 54 is carried on the inner end portion of the stem 50 between the cross head 15 and the stop 53, so that it normally holds the stem 50 outwardly in the guide 51, thus causing the inner part 41 of the male die to normally be spaced or removed from the outer part 40 in the manner illustrated at the left in Fig. 2. Stop 53 engages the end of the guide 51 to limit the outward movement of the stem 50. The amount that the stem 50 extends outwardly in the guide 51 may be regulated by suitable adjustment of the stop 53.

The finger 42 is slidably carried in openings 60 and 61 formed concentrically in the stem 50 and inner part 41, respectively. There is a head 62 on the inner end of the finger 42. The head 62 is slidably carried in a suitable opening 63 formed concentrically in the stem 50. A helical spring 64 is arranged in compression between a plug 65 adjustably removably carried in the end of the stem 50, and the head 62. The spring 64 normally moves the finger to its outermost position in which position it extends considerably beyond the inner part 41. The head 64 limits the outward movement of the finger 42. The amount that the spring 64 is under compression may be suitably adjusted or regulated by adjusting the position of the plug 65 in the end of the stem 50. When the finger 42 is in its innermost position its outer end forms a continuation of the surface 52 of the inner part 41.

The operating mechanism 13 provided by the present invention for operating the die mechanism comprises generally, a drive shaft 68 adapted to be operated through a pulley 69, a shaft 70 operated from the shaft 68 through suitable bevel gears 71, crank disks 72 mounted on the shaft 70, crank pins eccentrically mounted on the disks 72, and connecting rods 74 connecting the crank pins 73 with the cross head 15. The particular operating mechanism herein set forth embodies two crank disks 72, two crank pins 73, and two connecting rods 74 merely in order that the cross head 15 may be driven from both sides

to eliminate any tendency for it to bind on its guides 16. It will be obvious, of course, how the invention may be carried out with a single crank disk, crank pin, and connecting rod. In the particular machine shown

in the drawings the connecting rods 74 are directly pivotally connected to the crank pins 73 but are not directly pivotally connected to the cross head 15. The cross head 15 has suitable pivot pins 76 extending from it.

Suitable blocks 77 are carried on the pins 76 and suitable guide ways 78 are provided in the connecting rod to slidably carry the blocks 77. Compression springs 79 are arranged between the ends of the guide ways 78 and the blocks 77 to normally yieldingly hold the blocks 77 centrally between the ends of the guide ways.

The crank pins are eccentrically carried on the crank disks 72 so that they tend to move the cross head a distance greater than the distance between the female dies 11. The male die is therefore moved into co-operative engagement with the female die before the cross head has

reached the end of its stroke or movement and when the crank pins 73 are in the position shown in Fig. 8. Movement of the crank pins from the position shown in Fig. 8 to that shown in Fig. 9 tends to further move the male die in the direction of the female die.

The female die being solidly mounted in the frame 10 prevents movement of the male die and therefore causes the overtravel of the operating mechanism to be taken up by springs 79. However, as the

springs 79 are compressed in taking up the over travel of the operating mechanism the male die is held with greater pressure in the female die. It will be obvious that the pressure with which the male die is held in the female die will depend upon the amount of overtravel of the mechanism and upon the strength of the springs 79.

In accordance with the present invention means is provided in connection with the die mechanism to cause relative rotary movement between the two parts of the die mechanism while they are in co-operative position, or are together as shown in Figs. 8, 9 and 10. In the present form of the invention the male die is supported or carried by the retaining ring 45 so that it can be turned or rotated. A suitable bracket 80 attaches to the male die and an arm 81 extends from the brackets 80 and engages a cam 82 mounted on one of the connecting rods 74. The various parts just described are arranged and proportioned so that the cam 82 moves the outer part of the arm 81 vertically during

the time that the crank mechanism overtravels thus causing the male die to be rotated between the positions shown in Figs. 5 and 6. This particular means rotates the male die through only a few degrees as that is all that is necessary for effective opera-

70

130

tions of the present machine. It will be understood, however, that various mechanism may be provided for rotating a part of the die mechanism and that the means provided in any particular machine may be such as to cause the proper amount of rotation of the die parts.

The particular feed mechanism provided by the present invention comprises, generally, a platform or table 85 adapted to carry the sheets of paper which are to be cupped, feed rollers 87, a carrier for carrying the paper from the table to the feed rollers and suitable guide means for the paper. The sheets of paper A are arranged in a pile on the table 85 and are held in the proper piled relation by a suitable finger 89 carried in guides 90 and held in engagement with the top sheet of the pile by a suitable spring 91.

20 The carrier 86 is a pneumatic device and comprises a cylinder 92 connected to the crosshead 15 by an adjustable connecting rod 93, a plunger 94 arranged in the cylinder 92 and carried on a rod 95 which connects to a stationary frame member 96, and a tube 97 in communication with the cylinder 92 and adapted to have its outer end brought into engagement with the top sheet of the pile of papers A on table 85. An annular tip 130 of rubber or the like is preferably mounted on the outer end of the tube 97 to engage the sheets of paper. The connecting rod 93 is pivotally connected to the forward end of the cylinder and is loosely adjustably connected to the cross head, while the rod 95 is loosely connected to the frame member 96. The connections of the various parts are such, therefore, that the cylinder and plunger can be moved vertically. When 40 the cross head 15 is in, so that the male die is in place in the female die, the plunger 94 is at the forward end portion of the cylinder 86. As the cross head moves outwardly, carrying the male die away from the female die, it carries with it the cylinder 36 thus causing the plunger 94 which is held stationary, to move through the cylinder toward the rear end thereof. This movement of the plunger relative to the cylinder tends 50 to decrease the pressure in the forward end of the cylinder or to rarify the air in the forward end of the cylinder. When the cross head is in and the plunger is at the forward end of the cylinder the tip 130 at 55 the end of the tube 97 is in engagement with, or is closed by, the top sheet A of the pile of paper on table 85. As the plunger moves in the cylinder, as above described, decreasing the pressure in the outer end thereof, and 60 therefore in the tube 97 the top sheet A of the pile of paper on the table 85 is held at the end of the tube 87. As the cylinder is moved by the cross head in the manner described rollers 98, which are connected with 65 the cylinder by suitable arms 99, engage an

inclined cam track 100. The cam track 100 causes the cylinder and therefore the various parts of the carrying mechanism to move upwardly as well as outwardly thus causing the sheet of paper at the end of the tube 97 to be lifted from the pile on table 85 and be carried to the feed rollers 87. In practice the finger 89 and the spring 91 in connection therewith permit of the upper sheet of paper being pulled or removed from the pile of paper on the table 85 in the manner just described. In the preferred form of the invention suitable guide members 101, say in the form of wires, are provided to keep the sheet of paper, being carried by the carrier, substantially flat on a suitable guide table 102 so that it will be fed in a smooth flat condition to the feed rollers 87.

The feed rollers 87, which are preferably comparatively narrow, are mounted on a 85 rotating shaft 108 so as to engage the middle portion of the piece of paper fed to them by the carrier 86. The feed rollers 87 rotate in the direction indicated by the arrow in Fig. 7 and carry the paper over an idler 90 roller 109 yieldingly held upwardly against the guide rollers by suitable springs 110. The shaft 108 may be rotated at the proper speed, or in synchronism, with the other parts of the machine through any suitable drive mechanism, say a belt drive mechanism such as is shown in the drawing. As the paper passes from between the feed rollers and the idler roller it is turned and directed downwardly by guide rollers 111. After passing the guide rollers 111 the paper passes downwardly between a face plate 112 and a plurality of suitable guide wires or members 113. The face plate 112 and guide members 113 direct or guide the sheet of paper downwardly to a position directly in front of the female die 11, or to a position at the mouth of the female die 11. In practice, suitable stops 115 limit the downward movement of the paper between the face 110 plate 112 and the guide members 113. Further it is preferred that a suitable projection 116 be provided on the face plate 112 immediately above the center portion of the female die in order to bend or deflect the 115 sheet of paper outwardly as it passes between the face plate and the guide members so that it will not catch on the edge of the female die.

After the carrier 86 has delivered the sheet 120 of paper to the feed rollers 87 and upon inward, or return, movement of the cross head 15 the rollers 98 engage a suitable cam track 120 suitably spaced from the cam track 100. The cam track 120 causes the cylinder 92 to move inwardly and downwardly until the tube 97 engages the top sheet of the pile of paper on table 85.

From the foregoing description it will be readily understood how a sheet of paper A 130

is automatically fed or delivered into position in front of the female die 11 while the male die is removed from the female die thus causing the sheet of paper to be between 5 the male die and the female die. As the male die is moved toward the female die the finger 42, in extending from the inner part 41 of the male die, engages the center of the paper and holds or clamps it to the head 34, 10 of the finger 20 extending from the inner part 19 of the female die. The fingers 20 and 42 co-operate to engage or clamp the center of the paper before any other parts of the die mechanism are brought into co-operative engagement and continue to hold or clamp the 15 paper to hold it centrally in the die mechanism throughout the operation of the die mechanism. After the paper has been gripped by the fingers 20 and 42 and as the 20 male die continues to move toward the female die, the finger 20 moves inwardly in the inner part 19 of the female die against the resistance of spring 38 until the head 34 is seated in the recess 35. The finger 42 then 25 moves inwardly in the inner part 41 of the male die against the resistance of the spring 64 until the inner part 41 of the male die engages the paper and presses it against the inner part 19 of the female die. The inner 30 part 41 of the male die, is, of course, shaped to accurately fit the inner part 19 of the female die so that the entire center portion of the sheet of paper is clamped or shaped between these die parts. 35 As the operation continues, the inner part 19 of the female die is pressed or moved inwardly in the outer part 18 of the female die against the resistance of spring 30 until it is seated in the outer part 18 and the outer 40 part 40 of the male die engages the paper and presses it against the outer part 18 of the female die. The outer part of the male die accurately fits the outer part of the female die so that the outer portion of the 45 sheet of paper is clamped or formed between these two die parts. The successive movements of the various parts of the die mechanism, are, of course, due to the relative strengths of the springs which resist the 50 movement of the various parts of the die mechanism. At the same time that the outer portion of the paper is clamped between the surfaces 27 and 47 of the outer die parts 18 and 40, respectively, the periphery portion of the 55 sheet of paper is clamped or pressed between the surfaces 48 and 49 of the outer part 40 and the outer part 18, respectively. The surfaces 48 and 49 co-operate to form a flange at the 60 edge of the cup formed by the other parts of the dies. As the operating mechanism continues to operate, as hereinbefore described, the sheet of paper is tightly pressed between the two die parts and is ironed by the rotation of the male die part. The ironing of 65 the paper between the die parts while they

are held together with considerable pressure causes the paper to be permanently pressed or shaped so that it will retain the form of the die after it has been removed from the machine.

70

In the preferred form of the invention means is provided for heating the die mechanism in order that the paper will be pressed and ironed hot. In the present machine an electric heating element 140 is arranged 75 around the outer part 18 of the female die 11. It has been found in practice that the heating element around the outer part of the female die will properly and effectively heat the entire die mechanism.

80

After the sheet of paper has been formed, pressed and ironed, the male die is moved away from the female die allowing the fingers and inner parts of the die parts to eject the cupped sheet of paper from the die mechanism.

85

Having described only a preferred embodiment of my invention, I do not wish to limit myself to the specific details hereinabove set forth, but wish to reserve to myself any changes or variations that may appear to those skilled in the art or that may fall within the scope of the following claims.

90

Having described a preferred form of my invention, I claim:

95

1. In a machine for cupping paper, two co-operating die parts, one of the die parts including two relatively movable paper cupping portions normally spaced apart and adapted to fit together, and means for moving the die parts together so that said portions cooperate with the other die part to successively cup different portions of the paper in a single operation of the machine.

100

2. In a machine for cupping paper, two co-operating die parts, one of the die parts including two relatively movable paper cupping portions normally spaced apart and one adapted to seat on the other to form a continuation thereof, means for moving the die parts together so the said portions cooperate with the other die part to successively cup adjacent portions of the paper in a single operation of the machine.

105

3. In a paper cupping machine, two co-operating die parts, means for moving the die parts together with pressure to cup the paper, and means for causing relative rotation between the die parts while they press the paper to iron the paper.

110

4. In a paper cupping machine, two co-operating die parts, one of the die parts including a plurality of relatively movable paper cupping portions adapted to successively cooperate with the other die part to successively cup different parts of the paper upon movement of the die parts together, and means for causing relative rotation between cooperating die parts to iron the cupped paper.

115

120

125

130

5. In a paper cupping machine, two co-operating die parts, means for moving the die parts together with pressure to cup the paper, means for heating the die parts, and means for causing relative rotation between the die parts while they press the paper to iron the paper. 65
6. In a paper cupping machine, two co-operating die parts, one of the die parts including a plurality of relatively movable paper cupping portions adapted to successively cooperate with the other die part to successively cup different parts of the paper upon movement of the die parts together, 70 means for heating the die parts, and means for causing relative rotation between co-operating die parts to iron the cupped paper. 75
7. In a paper cupping machine, two relatively movable cooperating die parts, one of the die parts including two relatively movable paper cupping portions adapted to successively cooperate with the other die part to successively cup different parts of the paper upon movement of the die parts together, 80 and fingers carried by the die parts to cooperate to hold the paper while the die parts are moving together and before the die parts operate on it. 85
8. In combination two cooperating die parts, one of the die parts comprising a plurality of relatively movable portions adapted to operatively engage the other die part at different times during movement of the die parts together, means for moving the die parts together and holding them in pressure engagement, and means for rotating one of the die parts relative to the other while they are held in pressure engagement. 95
9. In a paper cupping machine, a female die comprising an outer portion and an inner portion normally spaced from the outer portion and adapted to be actuated to form a continuation of the outer portion, and a male die comprising an outer portion, and an inner portion normally spaced from the outer portion and adapted to be actuated to form a continuation of the outer portion, the male and female dies being shaped and adapted to be moved together so that the inner portions cooperate to cup a portion of the paper and actuate each other so that the outer portions cooperate to cup another portion of the paper. 100
10. In a paper cupping machine, a male die, a female die, each of said dies comprising an outer part, an inner part normally extending from the outer part and adapted to be actuated to form a continuation of the outer part, and a central finger normally extending from the inner part and adapted to be actuated to a position where it does not extend from the inner part, and means for moving the dies together causing first the fingers to cooperate to hold a piece of paper 105 and actuate each other, then the inner parts to cooperate to cup a portion of the piece of paper and actuate each other, and then the outer parts to cooperate to cup another portion of the piece of paper. 110
11. In a paper cupping machine, a male die, a female die, each of the dies comprising an outer part and an inner part normally extending from the outer part and adapted to be actuated to a position where it forms a continuation of the outer part, 75 means for actuating the dies so that the inner parts cooperate to cup a portion of the paper and actuate each other and then the outer parts cooperate to cup another portion of the paper adjacent the portion of the paper cupped by the inner parts, and means for rotating one of the dies relative to the other. 80
12. In a paper cupping machine, a male die, a female die, each of the dies comprising an outer part and an inner part normally extending from the outer part and adapted to be actuated to a position where it forms a continuation of the outer part, 85 means for actuating the dies so that the inner parts cooperate to cup a portion of the paper and actuate each other and then the outer parts cooperate to cup another portion of the paper, means for heating the dies, and means for rotating one of the dies relative to the other when the dies are completely actuated to iron the paper. 90
13. In a machine of the character described, a frame, two oppositely disposed die parts carried in spaced relation by the frame, two die parts connected together and movably carried by the frame so that they can be actuated so that each one cooperates with one of the first mentioned die parts, and a single operating mechanism for said movable die parts. 100
14. In a machine of the character described, a frame, two oppositely disposed die parts carried in spaced relation by the frame, a cross head slidably carried by the frame between said die parts, die parts mounted on opposite sides of the cross head, and means for reciprocating the cross head so that each of the die parts thereon cooperates with one of the first mentioned die parts. 110
15. In a machine of the character described, two cooperating dies one adapted to be moved relative to the other, a crank mechanism having a reciprocating movement greater than the movement of the movable die, and means connecting the crank mechanism and movable die so that the crank mechanism moves the movable die into engagement with the other die and then holds it in pressure engagement with the other die. 120
16. In a machine of the character de- 125

scribed, a frame, two oppositely disposed die parts carried in spaced relation by the frame, two die parts connected together and movably carried by the frame so that they can be actuated so that each one cooperates with one of the first mentioned die parts, and a single operating mechanism for said movable die parts, said mechanism embody-

ing yielding means whereby it operates to bring the cooperating die parts into yielding pressure engagement. 10

In witness that I claim the foregoing I have hereunto subscribed my name this 19th day of May 1921.

WALTER R. SCHINDLER.
